PROCESS FOR THE STERILIZATION AND
PRESERVATION OF EGGSJoseph Fousek, San Francisco, Calif., assignor to
Ovolo Incorporated, a corporation of CaliforniaNo Drawing. Original No. 1,852,606, dated April
5, 1932, Serial No. 278,037, May 15, 1928. Application
for reissue February 16, 1934, Serial No.
711,618

17 Claims.

(Cl. 99—161)

The present invention relates to a new and useful process for sterilizing and preserving eggs for commercial purposes, and includes the preserving of the whole of broken eggs, their whites or yolks separately, or any desired proportionate mixture of whites and yolks, the product secured from thus processing eggs being of a character and put up in such form as to best meet the requirements and conveniences of the trade.

10 It is to be understood that throughout this specification the term "egg" applies generically to any and all eggs, but more particularly to those of the domestic fowl, and that it is also intended to apply to the whole egg as removed from the shell, or to the whites, or to the yolks, or to the whites and yolks combined in any desired proportions.

The present process for the sterilization and preservation of eggs has been developed since 20 the issuance of my Patent No. 1,597,186, of August the 26th, 1926, and results from the experience gained in connection therewith, coupled with the research work connected with my applications for patents, Serial No. 190,654, filed May the 11th, 25 1927, and Patent No. 1,724,078.

It was learned from the experiments conducted in connection with the above noted processes for egg preservation that, with a properly proportioned mixture of egg, sugar and syrup, reduced 30 to complete emulsification and subjected to a right temperature, the product thus produced became possessed of excellent keeping qualities. Additional research also disclosed that the addition of the saccharine matter coupled with the emulsification process acted directly for the immediate separation from the egg body of all membranous, protoplasmic and like constituents entering into the egg structure and that the removal of these gave a greatly improved product 35 as to quality, together with a much extended period of preservation to this refined product when unsealed. Further investigation also developed that certain others of the carbohydrate group possessed the property of effecting this separation, as did also certain of the polyhydric alcohols, such as mannitol, glycerin and glycol, and that under treatment by any of these there resulted a product of a uniform excellency of character that, when properly sterilized and sealed 40 in containers, became possessed of qualities enabling it to be kept without impairment indefinitely, regardless of climatic conditions.

The primary object of my invention is the sterilization and preservation of eggs without impairment as to quality, whether as a whole, as

whites, as yolks, or as whites and yolks in any desired proportionate quantities.

Objects additional to the foregoing are:

To so process and preserve eggs in bulk as to fit them for substitution for fresh eggs, in the 5 culinary arts and elsewhere, where excellency of results are required and are so greatly dependent upon the quality of the eggs used;

To so process and preserve eggs in bulk as to cause them to retain in full measure those essential physical and chemical characteristics found in the fresh egg, and to prevent that denaturalization of proteins and degeneration of the egg substance commonly known as "watering 10 of the whites";

To so process eggs for their preservation as to destroy all bacteria without affecting the character of the physical and chemical constituents 15 of the eggs;

To cheaply sterilize and preserve eggs without 20 impairment, as a contributing means to the prevention of that waste in the egg industry resulting from the perishable character of eggs;

To so sterilize, preserve and seal eggs in a container as to insure keeping indefinitely and unimpaired under all climatic conditions, and as best 25 facilitates their handling in shipping;

To supply the market with a sterilized preserved egg product, properly prepared, proportioned and standardized for immediate use and 30 of a quality insuring uniformity of results in the arts utilizing eggs in their products;

To provide a sterilized preserved egg product adapted to meet the different requirements of the diverse arts employing eggs in their products, by 35 varying the proportions of water, albumen, yolk, and a selected carbohydrate, or its equivalent of polyhydric alcohol, entering into the completed product;

To provide a cheapened labor-saving sterilized 40 preserved egg product freed from all membranous and protoplasmic particles, and of a character readily assimilable by all doughs and particularly valuable in the production of the finer and more delicate bakery products, such as lady-fingers, sponges, etc.; and, finally;

To supply to the general trade, and to others, a processed egg product of superior quality and clear honey-like consistency, from which, at an earlier stage, has been removed all those elements 50 of inferior food values and most subject to deterioration, leaving, as a refined product, those elements, only, possessed of fresh egg qualities.

As is well known, it is common practice in the art of baking, after breaking and mixing the 55

eggs, to allow them to stand for a period of from three to five days to "ripen", this "ripening" process being of a disintegrating character causing the separation of the membranous and protoplasmic portions from the egg-body proper, the former, being the lighter, rising to the top, from whence it was removed and rejected as worthless. In my process, this step is not delayed but is of, practically, immediate accomplishment. Nor is there need of any sacrifice of removed elements as waste, since these, too, are sterilized and hermetically sealed for later use in the making of macaroons and such like delicacies.

The invention resides in the incorporation with the egg content of a variable amount of a suitable carbohydrate, or its equivalent of a polyhydric alcohol, such as glucose, fructose, saccharose or mannitol, glycerin, or glycol, these acting to separate the membranous and protoplasmic portions of the egg from its watery, albuminous and protein portions, while, at the same time, raising the coagulating temperature of the egg albumen from a matter of 140 degrees Fahrenheit, at which the ordinary bacteria would be immune, to an approximate 170 degrees Fahrenheit, a temperature insuring the destruction of the bacteria and perfect sterilization of the product when subjected to it, without impairment of the quality of the product through partial or complete coagulation of the albumen.

The proportion of carbohydrate, or of its equivalent of a polyhydric alcohol, used may vary considerably, but most essentially must be confined within the limits affecting markedly the physical structure of the egg liquid and the heat protective action upon the colloid present in the whites and yolks of the eggs, these proportions varying safely, by weight, from 1:1, 3:2 or 2:3, any of these ratios meeting successfully the requirements of the process.

My process for the sterilization and preservation of eggs is substantially as follows:

1. The eggs, after removal from their shells, are weighed and placed in a mechanical mixer;

45 2. To the eggs are now added the required proportion of a suitable carbohydrate, or its equivalent of polyhydric alcohol;

3. The composition thus secured is thoroughly mixed to a state of perfect emulsification;

50 4. After emulsification, the mass, now of syrup-like consistency, is allowed to stand for a short time to permit loosening and separation of the membranous and protoplasmic portions from the watery, albuminous and protein portions;

55 5. Following this, comes the removal of the membranous and protoplasmic portions, by skimming, straining or centrifugal separator action;

60 6. The two products thus secured are now separately subjected to a germ-destroying heat for a time and immediately thereafter hermetically sealed in containers.

While the main purpose sought is the production of a refined preserved sterilized egg product, it is obvious that three distinct products may result from the process, the first containing the entire egg, the second only the refuse or membranous and protoplasmic portions, and the third the refined albuminous and protein portions.

70 7. It is realized that others have used either sugar or glycerin in connection with egg preservation, the one used being dependent upon whether freezing or dehydration was to enter into the process; if the former, the sugar acting ordinarily to prevent reaching a temperature suffi-

ciently low to affect the physical properties of the protein; and, if the latter, the glycerin acting to protect against deterioration of the physical and chemical properties through a too drastic dehydration.

I claim and desire to secure by Letters Patent of the United States, the following:

1. The herein described process of preserving eggs which comprises introducing into a broken egg mass a carbohydrate for the purpose of causing the separation of the membranous, protoplasmic and fibrous portions of the egg structure from the remaining portions thereof, emulsifying the egg and carbohydrate mixture, allowing said mixture to settle, and thereafter separating the fibrous portions therefrom.

2. The herein described process of preserving broken eggs which comprises adding a carbohydrate thereto in sufficient quantity to loosen the membranous, protoplasmic and fibrous structure of the egg, mixing and emulsifying thoroughly, allowing the admixture to settle, then skimming said loosened membranous, protoplasmic and fibrous structure from the remaining portions of the egg and finally straining said remaining egg liquid to clarify the same.

3. The herein described method of preserving egg contents which comprises mixing a selected carbohydrate therewith in proportions varying from 3:2 to 2:3, by weight, thoroughly emulsifying the mixture, allowing said mixture to settle, and then straining it.

4. The process of substantially sterilizing and preserving egg contents which comprises adding to the egg contents an amount of a carbohydrate sufficient to raise the temperature of coagulation thereof upon application of heat, emulsifying the resulting product, permitting the emulsified mass to stand until the membranous and protoplasmic portion is separated out, removing said membranous and protoplasmic portion, and heating the remaining portion to destroy the contained germs.

5. The process of preserving egg contents which comprises adding thereto an amount of carbohydrate sufficient to raise the temperature of coagulation thereof when heat is applied, emulsifying the resulting product, permitting the emulsified mass to stand until the membranous and protoplasmic portion is separated out, and heating the membranous and protoplasmic portion to destroy the contained germs.

6. The herein described process of preserving eggs which comprises forming an emulsion of egg contents with glycerin, causing the admixture to settle and separating fibrous material therefrom.

7. The herein described process of preserving eggs which comprises forming an emulsion of egg contents with sugar, causing the admixture to settle and separating fibrous material therefrom.

8. An homogeneous substantially preserved egg mass containing a water-soluble, edible, polyhydric preservative of the class consisting of carbohydrates, glycol, glycerin and mannitol and substantially devoid of fibrous material to an extent not procurable by the customary ripening treatment, whereby the keeping properties of said egg mass are materially enhanced and the texture of products baked therewith materially improved.

9. A heat-treated homogeneous egg mass containing at least 40% by weight of a water-soluble, edible, polyhydric preservative of the class consisting of carbohydrates, glycol, glycerin and

- mannitol and substantially devoid of fibrous material to an extent not procurable by the customary ripening treatment, whereby the keeping properties of said egg mass are materially enhanced and the texture of products baked therewith materially improved.
10. An intimate mixture of egg contents and carbohydrate which is substantially devoid of fibrous material and coagulation products to an extent not procurable by the customary ripening treatment whereby the keeping properties of said egg mass are materially enhanced and the texture of products baked therewith materially improved and with substantially inhibited bacteria action.
15. 11. A substantially preserved intimate mixture of egg contents and sugar which is substantially devoid of fibrous material to an extent not procurable by the customary ripening treatment, whereby the keeping properties of said egg mass are materially enhanced and the texture of products baked therewith materially improved.
20. 12. An homogeneous egg mass containing from about 40% to 60% by weight of sugar and substantially devoid of fibrous material and active germs to an extent not procurable by the customary ripening treatment whereby the keeping properties of said egg mass are materially enhanced and the texture of products baked therewith materially improved.
25. 13. An homogeneous liquid egg mass containing glycerin and substantially devoid of fibrous material to an extent not procurable by the customary ripening treatment, whereby the keeping properties of said egg mass are materially enhanced and the texture of products baked therewith materially improved.
30. 14. An homogeneous, heat-treated liquid egg mass substantially devoid of fibrous material to an extent not procurable by the customary ripening treatment, whereby the keeping properties of said egg mass are materially enhanced and the texture of products baked therewith materially improved and containing at least 40% sugar.
35. 15. The herein described process of preserving eggs which comprises forming an emulsion of egg contents with an edible, water-soluble preservative of the class consisting of carbohydrate, mannitol, glycerine and glycol, causing the admixture to settle and separating fibrous materials therefrom.
10. 16. Preserved clear liquid egg mass comprising a preserving quantity of sugar and of honey-like consistency, said product having been heat-treated to obtain a substantially inhibited micro-organism action and whose normal fibrous content has been substantially removed to an extent 15 not procurable by the customary ripening treatment whereby the keeping properties of said egg mass are materially enhanced and the texture of products baked therewith materially improved.
15. 17. The herein described process of preserving eggs which comprises forming an emulsion of egg contents with sugar, allowing the mass to stand for a time sufficient to loosen and separate fibrous material from the mass proper; subjecting the emulsion to centrifugal force, where- 20 by the fibrous material is substantially completely removed and subjecting the centrifuged mass to a heat treatment above 140° F. but below that temperature at which substantial coagulation of albumen would take place.
25. 30. 35. JOSEPH FOUSEK.
